No. 779,103.

UNITED STATES PATENT OFFICE.

WILLIAM P. SLENSBY, OF NEW YORK, N. Y.

NEEDLE-THREADER.

SPECIFICATION forming part of Letters Patent No. 779,103, dated January 3, 1905.

Application filed April 20, 1903. Serial No. 153,356.

To all whom it may concern:

Be it known that I, WILLIAM P. SLENSBY, a citizen of the United States, residing in the borough of Brooklyn, in the city and State of New York, have invented a certain new and useful Improvement Relating to Needle-Threaders, of which the following is a specification.

The invention relates to that class of needle-threaders in which a sufficiently thin piece of metal, which I will call a "hook-bar," is received in the eye of the needle and caused to extend through. The portion of the hook-bar extending through is then engaged with the thread, and a return movement of the parts relatively to each other, either the withdrawal of the hook-bar or a retreating movement of the needle, draws the bight of the thread through the eye. It is easy to afterward straighten the bight. I prefer the ordinary fashion of moving the needle relatively to the hook-bar. I make the hook-bar tapered and provide a series of hooks like closely-set teeth. Each tooth is bent near its point, so that fabrics or other materials pressing gently against the thimble may be moved longitudinally thereof without abrasion; but a force urging the thread directly into the notches will be certain to engage it with one of them. I mount this hook-bar in a thimble so conditioned that it matches with the other portions of the thimble and involves no difficulty. I provide a groove in the thimble, in which the needle is held in engaging it with the end of the hook-bar. I provide for holding the hook-bar reliably in the correct position without soldering; but solder may be applied in addition to my fastening, subject to the obvious objections of increasing the labor and more or less injuring the appearance.

The following is a description of what I consider the best means of carrying out the invention.

The accompanying drawings form a part of this specification.

Figure 1 is a side view of a thimble open end upward with a portion of the right side in central vertical section. Fig. 2 is a corre-

sponding view, quarter-turned. Fig. 2^a is a view corresponding to Fig. 2, but showing a modification. Fig. 3 is a horizontal section of a portion on the line 3 3 in Fig. 2. Fig. 4 is on a larger scale. It is a face view of what I term the "hook-bar." Fig. 5 is a cross-section on the line 5 5 in Fig. 4 seen from the left, and Fig. 2^b is a vertical section of a portion on the line 2 2 in Fig. 2^a.

Similar letters of reference indicate corresponding parts in all the figures where they appear.

I will first describe the invention as holding the thimble with the open side upward.

A is the body of the thimble, and A' the usual thickened rim. I form a shallow notch in the rim having a breadth corresponding to the width of the widest end of the hook-bar and form two horizontal cuts a' a² at lower levels in the upper portion of the body. The partially-freed metal between these slits I will term a "band." I form an aperture a³, extending upward and downward quite through in the side of the body, and a horizontal groove a⁴ at the lower end of such aperture.

B is what I term the "hook-bar." It is a thin strip of steel of tapering form and provided with a series of round-bottomed notches b, leaving between them a corresponding series of projections, which I will call "hooks" or "teeth." Each hook B' is formed with its lower face inclined and its upper face nearly or quite square. This hook-bar is preferably made from steel without temper, and the points of all the several hooks are bent by sufficient force delicately applied, so that the point of each extends nearly parallel to the axis of the hook-bar. This important portion of the implement must have sufficient strength to pull the thread through the eye. A coarse thread may be engaged in the notch in the thick portion and fine thread may be engaged in the lowest notch. Very fine needles would not allow the tapering bar to be thrust through so far as to expose more than the two lowest notches. The device is therefore adapted to

present in the wide portion great strength for large thread in threading large needles, and a

slender end, with teeth also therein, for treating small needles and thread. My device is thus able to treat a wide range of needles and thread.

- 5 The fact of the hook-bar being tapered makes it practicable to thread needles of different sizes, making the strength of the thick portion available for threading large needles with large thread, and the fact of the several 10 hooks being crushed down a little gives a rounded contour to the outer face, so that the needle or other object may slide over it better and gives a more effective hold on the thread when it has been forced down and properly engaged in any one of the notches.
- The horizontal score α^4 should be deep enough to allow an ordinary needle to be laid therein and present its eye properly to the end of the hook-bar, and the needle is engaged 15 with the hook-piece by thus applying it and moving it upward. In moving it up the needle rises out of the groove α^4 , causing the hook-bar to yield outward by its elasticity. It is easy to engage the thread with the hook-bar 20 when thus raised, and on moving the needle back downward to the groove again the thread remains engaged with the hook-bar and is drawn through the needle-eye. Then the main portion of the operation is completed. It is 25 easy afterward by the fingers or by another needle to open the bight and draw one of the ends of the thread completely through the eye, and the needle is threaded.

I hold the elastic hook-bar in the circumferential notch α in the rim by strong pressure radially toward and from the axis of the thimble. I will designate the metal of the thimble between the cuts α' and α^2 as A^2 , and the metal below the cut α^2 , between it and the hole α^3 , I will designate A^3 . The metal A^2 is bent outward beyond the ordinary adjacent surface of the thimble, and the metal A^3 may sometimes be bent inward within its ordinary position in the thimble. It is not very important how far these distortions are made in the first place; but they should be sufficient to allow the elastic tapered hook-bar B to be inserted from above. When it is adjusted properly in position, that portion of the thimble is subjected to the action of a press or to one or more gentle blows with a hammer, which brings the metal A^2 and A^3 back nearly to the original position. When this operation is completed, the upper end of the hook-bar is firmly grasped by the thimble, being held inward by the metal A^2 and held outward by the metal A^3 at the top and the metal A^3 at a lower level. My experiments indicate that this fastening will hold the parts reliably 55 without other fastening.

By reducing the thickness of the hooks from each other I am enabled to reduce the space occupied by the threader in the eye of the

needle, thus giving more room where the hook engages the thread to pass through the eye of 65 the needle than if hooks were of uniform thickness with the body of the threader.

Modifications may be made without departing from the principle or sacrificing the advantages of the invention. Soft solder or silver 70 solder or brazing may, if preferred, be used in addition to the fastening means described.

The aperture α^3 , extending upward and downward, is useful in allowing the hook-bar to lie with its surfaces practically flush 75 with the exterior and interior of the thimble; but this condition is not absolutely essential. The invention will serve usefully with that portion of the thimble slightly grooved or depressed vertically or even if allowed to remain in its ordinary fully-rounded condition.

I claim as my invention—

1. A thimble A having slits α' α^2 with the portion A^2 between deflected outward, forming an integral band adapted to hold a needle-threader substantially as herein specified. 85

2. A thimble A having slits α' α^2 with the portion A^2 between deflected outward, forming an integral band and a notch α in the rim adapted to hold a needle-threader substantially as herein specified. 90

3. A thimble A having slits α' α^2 with the portion A^2 between deflected outward, forming an integral band and a notch α in the rim in combination with a needle-threader engaged therewith by being clasped thereby, substantially as herein specified. 95

4. A needle-threader comprising a hook-bar of tapering form, carrying a series of hooks thinned toward the points, adapted 100 to serve with needles of varying sizes, in combination with a thimble, substantially as herein specified.

5. A hook-bar of tapering form, carrying a series of hooks having the points deflected 105 and the outer sides rounded in combination with a thimble having an integral band A^2 and engaged therein by compression of such band adapted to serve substantially as herein specified. 110

6. A hook-bar of tapering form, carrying a series of hooks having the points deflected and the outer sides rounded in combination with a thimble having an integral band A^2 and engaged therein by compression of such band, 115 the thimble having a notch α in the rim and a cross-groove α^4 in the body, all arranged to serve substantially as herein specified.

7. A hook-bar of tapering form, and carrying a series of hooks B' having the points deflected inward in combination with a thimble and engaged therein by compression of the parts thereon, the thimble having a notch in the rim and having an aperture α^3 , and a cross-groove α^4 in the body, all arranged to 120 serve substantially as herein specified. 125

8. A hook-bar of elastic material in combination with a thimble and extending longitudinally thereof, arranged to allow the hook-bar to be sprung outward by causing a needle to be engaged with the yielding end of the hook-bar and moved upward thereon, all substantially as herein specified.

In testimony that I claim the invention above set forth I affix my signature in presence of two witnesses.

WILLIAM P. SLENSBY.
